(57) **CLAIM**

I claim the ornamental design for a wrappable wallet, as shown and described.

DESCRIPTION

FIG. 1 is a perspective view of a wrappable wallet showing our new design in use;

FIG. 2 is a top view thereof with straps folded inward;

FIG. 3 is a top view thereof with straps folded outward;

FIG. 4 is a bottom view thereof with the straps folded outward;

FIG. 5 is an upper side elevational view thereof;

FIG. 6 is a lower side elevational view thereof;

FIG. 7 is a right side elevational view thereof; and,

FIG. 8 is a left side elevational view thereof.
